UNITED STATES PATENT OFFICE.

HENRY NERGE, OF NEW YORK, N. Y.

GAME.

Application filed August 31, 1923. Serial No. 660,295.

To all whom it may concern:

Be it known that I, HENRY NERGE, a citizen of the United States, residing in the borough of Manhattan, city, county, and State 5 of New York, have invented certain new and useful Improvements in Games, of which the following is a specification.

This invention relates to a game device which may be used in imitating the plays 10 of various games. One of the objects of the invention is to provide a game which requires some skill in playing it, while there is also the element of more or less chance involved in the game. A further object of the 15 invention is to provide a simple and cheap game board, upon which there may be caused to roll a suitable loose object, the board being constructed with a field-area on which the said rolling object may be manipulated 20 by the tilting of the board so as to roll the said object to a critical point of the field-area, from which point the player rolls the object down a declivity, attempting to position the said object into a previously selected 25 pocket of a series of pockets with which the board is provided.

These being among the desirable objects 30 of the present invention, the same consists of certain features of construction and combinations of parts to be hereinafter described and then claimed with reference to the accompanying drawings, illustrating one embodiment of the invention, and in which—

Fig. 1 is a plan of the device, the rolling 35 object being shown in full lines in one position and in broken lines in another position;

Fig. 2 is a longitudinal sectional view of the device; and

Fig. 3 is a similar sectional view showing 40 how the device may be tilted to play a game.

Referring to the drawings, there is located below the upper edge of the rim of a box 10, a board which provides a rectangular field-area 11 between the opposite sides of the 45 box. The field-area 11 lies in a horizontal plane when the box is resting on a level support. This field-area 11 may be perfectly plain or it may have any suitable representation as of a base-ball diamond printed 50 thereon.

At one end of the field-area 11 there is a declivity 12 which is preferably formed by an inclined plane, and at the other end of the field-area there is preferably located a 55 similar declivity 13, especially if it be desired to play a game requiring competitors.

At the lower ends of the declivities 12, 13, there are provided two series of pockets 14, 15, so that there is a series of pockets at each end of the board extending transversely 60 thereof.

There is provided for use in playing a game a loose irregular object 16 which is preferably ovaliform in shape. The rolling object 16 is placed upon the field-area 11 and the box 10 has to be manipulated by tilting it and tipping it sideways, with a view to causing the object 16 to roll down to a point at the edge of the field-area 11 which would be opposite to a selected one of the pockets. 70 The ridges 17 at opposite ends of the field-area 11 constitute the critical lines up to which the object 16 may be moved with more or less skill.

At the ridges 17 the declivities 12, 13 75 abruptly join the field-area 11, and said declivities are free from any pockets except at their lower ends; that is to say each series of pockets 14, 15 is spaced a considerable distance away from ridge 17. In consequence of this, if a player rolls the object 16 beyond the critical line 17, it will quickly roll down the declivity, so that the matter of positioning the said object into a previously selected pocket is one of chance. 80

Whatever the game to be played may be, it is desirable that each of the pockets have a legend giving it a particular name or value. The legends selected for a base-ball game imitation are arbitrary, and those 90 shown in Fig. 1 are merely exemplary. Any desired arrangement of pockets and number thereof may be provided.

When the device is constructed substantially as shown, the game of base-ball for 95 example is played by two persons who play from opposite ends of the board. One of the players will place the rolling object 16 at say that end of the field-area 11 which is adjacent the pockets 15 and by tilting and 100 manipulating the board the player will endeavor to roll the object 16 just down to the critical ridge 17 at the other end of the board. In doing this, the player will try to roll the object 16 to a point in substantial 105 alignment with a selected pocket, say one which calls for a hit, and this manoeuvring requires some little skill.

In rolling the object 16 to a selected position at ridge 17 the player will have to 110 occasionally tip the board sideways, as the irregular object 16 will not roll in a straight

line. Having rolled the object 16 to the desired point at ridge 17, the player may have to tilt the board still more which causes the object 16 to speedily roll down the declivity 5 12, and possibly, although not with certainty, into the selected pocket. There is more or less chance involved in positioning the object 16 in a selected pocket.

10 The other player then places the object 16 at the end of the field-area 11 which is adjacent the pockets 14 and having selected one of the pockets 15 in which to roll the object, tries to place the object into such pocket in a manner more or less similar to that adopted by the first player. Without further explanation, it will be perfectly obvious to those familiar with the game of base-ball what plays they should attempt to make in turn, as each series of pockets 15 20 will bear legends designating particular plays in the game of base-ball. Rules

should, of course, be laid down for playing whatever game the board is used for.

It is obvious that the device shown and described is susceptible of more or less modification and still be within the claims; for instance, the rolling object may be spherical, although the less certain direction of roll of an irregular object will probably create the greater interest in the game. 25 30

What I claim as new is:

A game, comprising a board with a field area, which is in a horizontal plane, and having an inclined plane constituting a declivity at one end of the field area, and a series of pockets spaced away from the field area and located at the bottom of the declivity, and extending in a direction parallel with the ridge at the juncture between the field area and the declivity. 35

HENRY NERGE.
